UNITED STATES PATENT OFFICE.

THEODORE C. BATES, OF NORTH BROOKFIELD, MASSACHUSETTS.

CORSET-STEEL FASTENING.

SPECIFICATION forming part of Letters Patent No. 239,919, dated April 12, 1881.

Application filed November 22, 1880. (Model.)

To all whom it may concern:

Be it known that I, THEODORE C. BATES, of North Brookfield, county of Worcester, and State of Massachusetts, have invented a new and useful Improvement in Corset-Steel Fastenings, of which the following description, in connection with the accompanying drawings, is a specification.

This invention in corset-steel fastenings is an improvement on the fastenings represented in United States Letters Patent No. 225,375, to which reference may be had. In that patent the fastening is held in place near the inner edge of the steel by the same rivets that secure the usual eye-piece to the steel. Such construction restricts the length of the spring part of the fastening to the distance between the said rivets and the inner end of the straight part of the stud-receiving eye, and necessitates a very thin or slight spring when sheet metal is used, it being in practice the best material, both for best work and appearance.

In this my invention I have made the laterally-moving stud-fastening spring quite long, have bent or curved it near its shank, so as to permit it to have an easy movement, and have fastened or fixed the said shank in position near the outer edge of that member of the steel with which it is intended to move.

In practice I have extended the eye-piece backward across the steel, or nearly so, and have attached the shank of the curved spring thereto, the eye-piece serving as a rest for the flat under side of the spring.

To insure true horizontal movement of the fastening-spring, I have provided a guide for its outer or free end, the said guide also holding the free end of the spring down in place. I have also provided the eye-piece with a stop to arrest the movement of the fastening-spring toward the center of the eye-piece and prevent the head of the headed stud of the opposing steel striking the under side of and lifting the fastening-spring as the stud is being inserted up through the eye.

Figure 1 represents, in plan view, two steels with one of my steel-fastenings applied to hold the steels together; Fig. 2, a plan view of the fastening unhooked from the headed stud; Fig. 3, a longitudinal section on the line $x-x$,

Fig. 2; Fig. 4, a cross-section on the line $y-y$; Fig. 5, a modification of my invention, and Fig. 6 a top view of an eye-piece with the spring omitted.

Referring to Figs. 1 and 2, the steels a and b headed stud d are all as usual.

The eye-piece c , provided with the usual round-ended stud-receiving eye 3 , and attached to the steel by the rivets e , has its end 2 extended backward substantially to the outer side of the steel. The upper side of this eye-piece is depressed or reduced along one edge to form a recess, h , (see Fig. 6,) to receive the sheet-metal fastening-spring f , which has a nose, n , to spring behind the stud d , as in Fig. 1, and prevent the stud from moving backward along the said slot into the enlarged part of the eye. This spring f is extended along the eye-piece to its rear end, when it is bent or curved, as at 5, and the shank 6 of the spring is then attached to the rearwardly-extended part 2 of the eye-piece, either by rivets, as in Fig. 1, or by a dovetail-connection, as in Fig. 5. The bend 5 permits the spring f to yield at a considerable distance from the nose n , which enables me to employ a strong spring, and one which may be employed with less liability of being broken. The free end of the spring is extended under the guide g , (shown as a small projection,) it preventing that end from rising, and guiding the end of the spring in its lateral movements effected by the pressure of the stud d against the nose n .

At the rear of the nose the eye-piece is provided with a stop, 4, which I prefer to employ to limit the forward movement of the spring. The outer portion of the said stop, being flush with the outer portion of the spring f , and being interposed between it and the eye 3 , forms a shield, so that the head of the stud d , when being inserted in the said eye 3 , cannot strike the under side of and lift the spring f from the eye-piece.

I claim—

1. In a corset-steel fastening, the eye-piece provided with a recess, h , combined with the long spring f , bent or curved near the outer edge of the steel at 5 to permit the spring to yield at that point, substantially as described.

2. The sheet-metal spring f , bent at 5 and 100

secured to the extended rear end, 2, and resting in recess *h* of the eye-piece, combined with the eye-piece *c*, having the guide *g*, to receive the free end of the said spring and hold and direct its movement, substantially as described.

3. In a corset-steel fastening, the long spring *f*, combined with the eye-piece, provided with the recess *h* about its edge to receive the said spring, and with a stop to limit the forward movement of the spring and obviate the head

of the stud striking the under side of the spring when the stud is being entered into the eye *3* of the eye-piece.

In testimony whereof I have signed my name to this specification in the presence of two *15* subscribing witnesses.

THEODORE C. BATES.
